(57) **CLAIM**

We claim the ornamental design for a cover for a telephone, as shown and described.

DESCRIPTION

FIG. 1 is a front view of a cover for a telephone showing one new design;

FIG. 2 is a top plan view of the cover of FIG. 1;

FIG. 3 is a bottom view of the cover of FIG. 1;

FIG. 4 is an enlarged side view of the cover of FIG. 1 taken from the right side thereof;

FIG. 5 is an enlarged side view of the cover of FIG. 1, similar to FIG. 4, taken from the opposite side;

FIG. 6 is an enlarged rear view of the cover of FIG. 1;

FIG. 7 is an enlarged front perspective view of the cover of FIG. 1 taken from the same side as FIG. 4; and,

FIG. 8 is an enlarged rear perspective view of the cover of FIGS. 1 and 7.
